UNITED STATES PATENT OFFICE.

CHARLES J. KIRK AND GEORGE BRAIN, OF NEW CASTLE, PENNSYLVANIA, ASSIGNORS TO UNIVERSAL SANITARY MANUFACTURING CO., OF NEW CASTLE, PENNSYLVANIA, A CORPORATION OF PENNSYLVANIA.

PROCESS AND MOLD FOR FORMING EARTHENWARE ARTICLES AND PRODUCT THEREOF.

Application filed April 6, 1922. Serial No. 550,212.

To all whom it may concern:

Be it known that we, CHARLES J. KIRK and GEORGE BRAIN, citizens of the United States, and residents of New Castle, in the 5 county of Lawrence and State of Pennsylvania, have invented a new and useful Improvement in Processes and Molds for Forming Earthenware Articles and Product Thereof; and we do hereby declare the following to be a full, clear, and exact description thereof.

Our invention relates to the art of forming earthenware articles, particularly cast porcelain water closets, and it constitutes an 15 improvement over the invention set forth and claimed in U. S. Letters Patent No. 952,745 granted to Charles J. Kirk March 22, 1910.

As described in Patent No. 952,745, articles of plastic material having tortuous passages, such as closet bowls, are cast by inserting in the mold a previously formed permanent core which forms an integral part of the completed article. When closet bowls 25 are thus cast, the permanent core is of the shape of the siphon member of the bowl and in the method shown in Patent No. 952,745 the lower wall of the siphon channel is spaced from the front and bottom walls of 30 the siphon member. When such a cast bowl is removed from the mold the porcelain is still soft and if, during drying and setting, it is subjected to shocks or vibrations the lower wall of the siphon channel is likely to 35 sink into the opening between this wall and the front and bottom walls of the siphon, thus spoiling the work.

Our present invention aims to improve 40 the manufacture of cast porcelain bowls of the character indicated by modifying the construction of the permanent core or siphon member so that the under side of the siphon channel shall be supported by a vertical wall which strengthens the siphon member and 45 prevents the porcelain from settling at this point during hardening. Specifically, we accomplish this result by casting the siphon member with a central web which connects the upper curved portion of the siphon with 50 its front and bottom portions.

The accompanying drawing shows, by way of example, the method of casting one typical form of closet bowl according to our present invention, it being understood, how-

ever, that the precise shape and arrangement 55 of parts may be varied to a considerable extent. Fig. 1 is a side elevational view of the closet mold with one of the side members removed, showing the permanent core and base ring in place; Fig. 2 is a longitudinal vertical sectional view taken centrally through the mold showing the mold filled with the liquid slip; Fig. 3 is a perspective view of the permanent core or siphon member; Fig. 4 is an end elevational view of the siphon 60 member of Fig. 3; Fig. 5 is a vertical sectional view through the siphon member, the section being taken substantially on the line 5—5, Fig. 1; and Fig. 6 is a vertical sectional view taken substantially on the line 70 6—6, Fig. 1, showing the structure of the finished article.

The parts of the drawing which are common to this application and to Letters Patent No. 952,745 are numbered as in the said 75 patent. As in this patent, the base block 1 of the mold is provided with a projecting portion 2, and a circular aperture 3 is provided through the base block for the discharge opening of the closet siphon. The 80 upper surface of the base block at this point is provided with a concentric circular portion 4, slightly raised and of less diameter than the width of the base of the finished article. The remaining upper surface of the 85 finished block is provided with a separate raised portion 5. The outer contour of the closet is formed by a mold centrally divided into two removable halves 6. The inner upper surface 7 of the bowl is formed by a depending member 8 carried by the top block 9. The top block is provided with a funnel-shaped aperture 10 which opens through the lower extremity of the bowl-forming member 8. The top block is also provided with a depending semi-circular member 11 projecting centrally from one end of the bowl-forming member 8 and received in a correspondingly shaped recess 12 in the walls of the mold members 6. A base ring 13 and a 95 previously formed permanent core or siphon member 14 are placed in the position shown in Fig. 1 upon the base block. The base ring 13 corresponds in diameter to the circular raised portion 4 of the base block and is provided with an aperture coinciding with the aperture 3 through the base block.

The siphon member 14 is of the form best

shown in Figs. 3 to 6. It consists of a base member 15, a front wall 16 and sides 17 which extend upwardly as shown at 18 to join the upper end of the front portion 16. 5 A vertical web 19 supports the rear portion of the receptacle formed by the wall 17, and another vertical web 20 is formed in the triangular space between the base 15, the front portion 16 and the inside of the receptacle 10 or channel member formed by the side walls 17. The base 15 is of the hollow curved construction shown in Figs. 4, 5 and 6, and the front member 16 is also made hollow, as shown in Fig. 4. 15 The base ring 13 and the siphon member 14 are cast separately and preferably from the same material as is used in the casting of the closet, or from some other material which will contract at about the same rate during 20 the setting and firing operations. The base ring and the siphon member are placed in the mold while they are still soft, in order that they will readily adhere to each other and to the slip. The mold is then filled with 25 liquid slip which enters all of the spaces between the sides of the siphon member, the base ring, the bowl-forming member 8 and the side members 6 of the mold. After the slip has been allowed to set for a sufficient 30 length of time a deposit 30 of porcelain forms upon the inner sides of the mold and envelopes the siphon member, as shown in Fig. 2. When this deposit is of the proper thickness, the closure 21 is removed from 35 the discharge opening 3 in the base block, and the remaining liquid is drawn off, leaving the completed closet bowl with its siphon passages and base member, and with the siphon member or core embedded in place. 40 The top block with the depending bowl forming member 8 is then removed, carrying away the deposit 31 on the upper surface of the member 8, and the flushing ring is attached in the usual manner, after which the 45 porcelain is set and fired.

Fig. 6 shows a section of the completed article on the line 6—6, Fig. 1. It will be observed that the side walls 17 of the channel portion of the siphon member are united 50 integrally with the vertical side walls 32, and also with the base portion 15 of the siphon member.

During the period of setting, the entire structure, including the siphon member 14, 55 is still soft, but the webs 19 and 20 prevent the walls of the siphon channel to sink, even though the article is subjected to considerable shock or vibration. We have found that the loss of ware through damage 60 of this kind is entirely eliminated.

A further advantage of this method is that a better union is produced between the permanent core or siphon member and the enveloping walls of porcelain, inasmuch as 65 the porcelain is deposited in the recess ad-

jacent to the webs 19 and 20 and upon the webs themselves.

We claim as our invention:

1. The process of forming a closet of cast earthenware which comprises providing a siphon member forming the top of the discharge arm of the siphon and the bottom of the intake arm of the siphon, the said member having the intake siphon portion supported throughout its length upon said discharge portion by means of a solid web, placing the said siphon member in a mold, forming the exterior of the closet bowl, and casting the said siphon member within the closet. 80

2. The process of forming a cast porcelain closet that comprises providing a siphon member, forming the inner surface of the siphon passageway, and having said surface portion supported from beneath throughout its length by means of a solid web, placing said siphon member in a mold conforming to the outer surface of the closet bowl, and casting said siphon member within the closet. 90

3. In a mold for casting siphon closets, the combination with top, side and bottom members conforming to the outer surfaces of the closet, of a core or siphon member of substantially the same material as the closet 95 conforming to the interior surfaces of the siphon walls, and having its upper portion which forms the lower wall of the siphon channel supported from beneath throughout its length by means of a solid web, the said siphon member being supported upon said base member and being adapted to be covered with a deposit of porcelain and to form a homogeneous part of the completed closet. 105

4. In a mold for casting siphon closets, the combination of top, side and bottom members conforming to the outer surfaces of the closet, of a permanent core or siphon member of substantially the same material 110 as the closet conforming to the bottom of the intake arm and the top of the discharge arm of the siphon, the said intake portion being supported upon said discharge portion by means of a solid web joining said portions, and said siphon member being supported upon said base member and being adapted to be covered with a deposit of porcelain and to form a homogeneous part 115 of the closet. 120

5. A permanent core or siphon member for use in casting earthenware closets comprising a base member, a channel member supported upon said base member, and solid means formed integral with said members 125 for supporting said channel member upon said base member.

6. A permanent core or siphon member for use in casting earthenware closets comprising a hollow base member, a channel 130

member supported upon said base member, and a solid web portion cast integral with said base and channel members for supporting the inside of said channel member.

5 7. A permanent core or siphon member for use in casting earthenware closets comprising a base member, a channel member supported on said base member and having an upward extension forming the under side 10 of the intake arm of the siphon in the completed closet, a front portion connecting the said extension and said base member, and a solid web formed integral with said base member, front portion and channel member, and serving to support the under side 15 of said channel member.

8. A permanent core or siphon member for use in casting earthenware closets comprising a base member, a channel member 20 supported on said base member and having an upward extension forming the under side of the intake arm of the siphon in the completed closet, a front portion connecting the said extension and said base 25 member, a web formed integral with said base member, front portion and channel

member, and serving to support the under side of said channel member, and a second web integral with said spaced portion and channel member for supporting the rear 30 portion of said channel member.

9. A cast porcelain siphon closet having a siphon portion comprising two spaced parallel walls and a siphon member disposed between said walls, said member having a downwardly curved upper portion forming the under side of the siphon intake channel, and an upwardly curved base portion forming the upper side of the siphon discharge channel, the said upper and lower 40 portions of said siphon member being integrally united to each other and to said side walls.

In testimony whereof, we the said CHARLES J. KIRK and GEORGE BRAIN have 45 hereunto set our hands.

CHARLES J. KIRK.
GEORGE BRAIN.
